F. MYERS,
RECORD NEEDLE REPOINTER,
APPLICATION FILED APR. 11, 1919.

1,331,850.

Patented Feb. 24, 1920.

Fig. 3.

Inventor
Frederick Myers

UNITED STATES PATENT OFFICE.

FREDERICK MYERS, OF NEW YORK, N. Y., ASSIGNOR TO MYERS PHONOGRAPH CORPORATION, A CORPORATION OF NEW YORK.

RECORD-NEEDLE REPOINTER.

1,331,850.

Specification of Letters Patent. Patented Feb. 24, 1920.

Application filed April 11, 1919. Serial No. 289,235.

To all whom it may concern:

Be it known that I, FREDERICK MYERS, a citizen of the United States, and a resident of New York, in the county of New York 5 and State of New York, have invented certain new and useful Improvements in Record-Needle Repointers, of which the following is a specification.

This invention relates to improvements 10 in devices for producing a smoothly finished conical point upon needles such as are used in connection with sound reproducing machines.

The principal object of the invention is 15 to provide a neat, small and compact apparatus adapted for manual operation, in which a needle may be repointed in a rapid and easy manner, the device being a desirable adjunct to a talking machine using 20 disk records.

A further object is to provide a mechanism which will repoint a needle central with its axis, irrespective of its length or condition, so that the same may be used 25 without scratching or damaging the record, and which will produce a point adapted for reproducing sound from records in a superior manner.

These and other like objects are attained 30 by the novel construction and combination of parts hereinafter described, and shown in the accompanying drawings, forming a material part of this disclosure, and in which:—

35 Figure 1 is a side elevational view showing a needle repointing mechanism made in accordance with the invention.

Fig. 2 is a front elevational view thereof, and

40 Fig. 3 is an enlarged fragmentary sectional view taken through the needle holding device.

Referring to the drawings, the numeral 10 designates the base of the mechanism, the 45 same being preferably provided with a cushion-like felt pad 11 upon its lower side so as to avoid scratching or defacing the surface upon which the machine is placed.

Fixedly engaged upon the upper surface 50 of the base 10 is a metal strip 12, having a vertical standard 14, bent outward at its upper end and formed so as to provide a pair of forks 15, in which, pivoted upon the pin 16, is a lever 17, having a front extending portion 18 terminating in an upturned finger catch 19.

Engaged with the opposite end 20 of the lever 17 is a coiled tensional spring 21, secured at its lower end to a pin 22, extending rearwardly from the standard 14. 60

The opposite end of the strip 12 is also turned vertically upward forming a front standard 24 and journaled in the standard 14 and 24 is a spindle 25, held in position by a collar 26, fixed upon the end extending 65 through the standard 14, while its front end, extending through the standard 24, has secured upon it a crank lever 28, in which is set an extending pin 29, for the rotatable knob or handle 30, whereby rotary 70 motion may be manually conveyed to the spindle 25.

Secured upon the spindle is the hub 31 of an abrading wheel 32, having a conical face for purposes which will be hereafter 75 described. Upon the opposite end of the spindle 25, is fixed the hub 34, of a spur gear 35, the gear meshing with a spur pinion 36, mounted on a spindle 37, rigidly secured in the lever 17, and extending toward the 80 front of the machine.

The pinion 36 is formed with a sleeve 38, having an annular enlargement 39, terminating in a reduced head 40, bored axially to receive a needle 52, the head containing 85 a conical recess 43, so that the straight portion of a needle may be readily entered and clamped therein by the thumb screw 44, the same having an enlarged knurled head which may be operated by the thumb and fingers. 90

At the inner end of the cylindrical recess 45, formed in the sleeve 38 to receive the spindle 37, is also contained a coiled compression spring 46, pressing outwardly a small plunger 47, against which the straight 95 end of the needle 42 abuts.

A spring arm 48 is secured to the base by the clamp screw 49, the same being curved and provided with an elongated opening 50 adapted to surround the head 48, and 100 press against the annular enlargement 49, holding the sleeve, together with the gear, upon the spindle 37 on which it rotates.

Secured upon the standard 24, by the pivot screw 51, is a plate arm or gage 52, having 105 an arcuate slot 53, inclosing the spindle 25, the arm being turned rearwardly as at 54, above the arcuate slot, and terminates in a roll or beaded end 55, to which it may be operated.

In order to hold the implement firmly upon the supporting surface an upturned

lug 57 is secured upon the base upon which the thumb of the operator's hand may be placed, while the other hand actuates the extending knob 30, communicating motion to the spindle 25, rotating the abrading wheel 32, and if the lever 18 be depressed, by action of the fingers, the pinion 36 will engage with the teeth of the gear 35, thereby communicating rotary motion to the sleeve 10 38, which is held rearwardly by the action of the spring arm 48.

The pivoted gage arm 52 being pushed to one side, as indicated best in Fig. 2, a needle may be readily inserted in the conical entrance 33, whereupon the arm 52 is raised to a vertical position acting as a limit or gage for the point of the needle, which is pressed forward, due to the action of the spring 46, and then clamped by manipulating the 20 thumb screw 44. The lever 52 is then moved again to the side, the finger pressed upon the lever 18, guided by the projection 19, so as to bring the gears into engagement and cause the conical end of the needle to 25 make contact with the revolving beveled surface of the abrading wheel 32, thereby re-pointing the needle in an obvious manner.

Immediately upon releasing the lever 18 it is raised by the pull of the spring 21, the 30 screw 44 relaxed and the needle removed, the operative position of the sleeve being indicated by the broken lines in Fig. 1.

From the foregoing it will be seen that a neat and easily operated device has been disclosed, whereby ordinary record needles may be re-pointed in a rapid and accurate manner.

It will be understood that minor changes may be made from the structure as presented, as for instance, the abrading wheel may 40 be geared to rotate at a higher rate of speed than by the crank directly as shown and various other modifications without departing from the general spirit of the invention herein recited.

Having thus described my invention what I claim as new, and desire to secure by Letters Patent, is:—

1. In a device of the class described, the combination with a base, a pair of standards 50 thereon, and a spindle journaled in said standards, of an abrading wheel secured upon said spindle, means for manually rotating said spindle, a lever journaled in one of said standards, a spindle extending from 55 said lever, a sleeve rotatable on said second spindle, driving connections between said sleeve and the first named spindle, means for normally raising said second spindle, a head formed with said sleeve having a conically 60 mouthed opening, means for clamping a needle therein and a swinging stop for locating the point of the needle.

2. In a device of the class described the

combination with a base, a pair of standards secured thereto, a spindle journaled in said standards, means communicating rotary motion to said spindle, an abrading wheel secured on said spindle at one end, and a spur gear secured upon said spindle at its opposite end, of a lever pivoted in one of said standards to move in a vertical plane, a spring attached to said lever whereby it is normally held in a raised position, means for depressing said lever, a spindle rigidly secured in said lever, a sleeve rotatable on 75 said second spindle, geared connections between said sleeve and the first named spindle, resilient means for holding said sleeve on said second spindle, a head formed with said sleeve adapted to receive a needle, means for 80 clamping said needle in position, and a swinging gage whereby a needle may be adjustably fixed in said head.

3. In a device of the class described, the combination with a base, and means for holding said base upon a support, of a pair of standards secured on opposite sides of said base, a spindle journaled in said standards, means for rotating said spindle, pivotal connections for said spindle whereby 85 it may be raised or lowered relative to the first named spindle, a sleeve rotatable on said second spindle, resilient means for holding said sleeve thereon, geared connections between said sleeve and the first named 90 spindle, a gage arm pivoted on one of said standards, said gage arm having an opening inclosing the first named spindle, means for operating said gage arm, a head formed in said spindle adapted to receive a needle, 95 means for clamping the needle therein, means for pressing the needle outwardly against said gage arm, and means for clamping the needle in position to make contact with said abrading wheel.

4. In a machine for grinding conical points on cylindrical rods, the combination with a horizontal shaft rotatably mounted in fixed bearings, and means for manually rotating said shaft, of an abrading wheel having a beveled face driven by said shaft, a pivoted support over said shaft, a spindle secured on said support, means for raising said spindle at an inclination relative to said shaft, a sleeve rotatable on said spindle, a bell-mouthed head carried by said sleeve receptive of a needle, means for adjusting the point of the needle relative to said abrading wheel, and operative connections between said shaft and said sleeve whereby the latter is driven when said support is manually depressed.

In testimony whereof I have signed my name to this specification.

FREDERICK MYERS.
